SPRING CONSTRUCTION.

1,352,574.

Specification of Letters Patent. Patented Sept. 14, 1920.

Application filed May 1, 1916. Serial No. 94,557.

To all whom it may concern:

Be it known that we, GEORGE W. BARNES and DON CARLOS TRAVIS, citizens of the United States, and residents of the city of Kenosha, county of Kenosha, and State of Wisconsin, have invented certain new and useful Improvements in Spring Constructions, of which the following is a specification.

- 10 This invention relates to improvements in spring constructions and refers more particularly to novel means for securing the coil springs of a bed bottom or similar article against lateral displacement.
- 15 Among the salient objects of the invention are to provide improved means for connecting the central parts of the helical spring members to each other so as to prevent lateral displacement of the coils without in any manner interfering with the resiliency of the spring frame structure as a whole; to provide a construction in which the connecting members above referred to can be economically made and are readily secured in place and in general to provide 25 an improved construction of the character referred to.

In the drawings—

Figure 1 is a fragmentary side elevation of 30 a spring construction embodying our invention.

Fig. 2 is a sectional view of the construction shown in Fig. 1.

Fig. 3 is a detail view showing the construction of the centrally disposed cross springs and wires.

We are aware that cross connecting straps or wires extending through the central part of helical springs are not broadly new, also 40 that it is not broadly new to use tie plates or tie members for securing the upper ends of such coils together. However, as far as we are aware no one has devised any construction such as that shown in the drawings, and

45 hereinafter more particularly described and which embodies the advantages of the present invention. In devices of this character the margin of profit is small and differences in details of construction which add even 50 slightly to the economy of construction and to easiness of assembling are frequently vitally important to the manufacturer.

In the particular embodiment of the present invention we have shown a bed construction comprising a plurality of helical coil

springs 1 secured between the upper and lower marginal frames 2 and 3 respectively. The central parts of the helical springs are tied together by means of a plurality of cross connecting members or straps 4 and 60 longitudinally extending wires 5. The particular manner in which the straps and wires are formed and interlocked with the helical springs, forms one of the salient features of the present invention. Each of these straps 65 4 is provided with a plurality of offset portions 6. Each offset portion is of a width substantially equal to the inside diameter of the central part of the helical spring and consists of a pair of right angle shoulder 70 portions 7 and a centrally disposed groove portion 8. Each wire 5 is also provided with a plurality of offset portions 9, each being of substantially the width of the inside diameter of the central coils of the helicals. Each offset portion 9 comprises a pair of right angle shoulders 10 and a second offset portion 11 formed by the right angle shoulders 12. The offset portions 11 are of 75 the same width as the straps 4 and are 80 adapted to fit in grooves 8 of the latter. When the straps 4 and wires 5 are assembled in position as shown more clearly in Fig. 3, the straps 4 and shoulder 10 of the wires 5 abut closely against the inner sides of the 85 coils of the helicals, at the same time the offset portion 11 of the wire fits snugly within the groove 8 and shoulder portion 12 of the offset portion 11 of the wire fits snugly within 90 the sides of the straps 4. The arrangement is such that not only are the helical springs themselves effectively locked against lateral displacement but the wires and straps are also so interlocked as to effectively prevent any displacement, irrespective of the springs. 95

It has been found in practice that this makes a simple and yet most effective lock and obviates the necessity of cutting or otherwise mutilating either the wires or the straps.

The invention is not limited to the details of construction shown except as set forth in the appended claims.

We claim as our invention:

1. In a spring construction, the combination with upper and lower marginal frame members, having coil springs interposed therebetween, of a series of flat cross-connecting members extending through the coils of the said springs and each provided with 105 110

- an offset portion of substantially less width than the coil, vertically extending shoulders connecting the offset portions to the main body of said cross-connecting member, said 5 vertically extending shoulders fitting closely against the adjacent sides of the coil, a depressed portion formed in the central part of each offset portion and a second series of cross-connecting members each having a 10 plurality of vertically extending shoulder portions fitting closely against the adjacent sides of the corresponding coils and second shoulder portions fitting against the adjacent sides of the offset portion of the flat 15 strap members, said last mentioned shoulders having a connection fitting within said depressed portion.
2. In a spring construction the combination with opposed frame members having 20 coil springs interposed therebetween, of a series of cross connecting members extend-

ing through the coils of the said springs and each provided with an offset portion, vertically extending portions connecting the offset portion to the main body of the cross 25 connecting link or member and fitting within the adjacent sides of the coil and a second series of cross connecting members each having a plurality of vertically extending shoulder portions fitting within the adjacent sides 30 of the corresponding coils and means intermediate of the vertically extending portions of the first mentioned series of cross connecting members detachably interlocked with means intermediate of the shoulder 35 portions of the second mentioned series of cross connecting members by the tension of the adjoining coils of the spring between which the members are interposed.

GEORGE W. BARNES.
DON CARLOS TRAVIS.
